UNITED STATES PATENT OFFICE.

WILLIAM ELLIS, OF HARROD, OHIO.

SPARK-PLUG.

1,024,321.

Specification of Letters Patent.

Patented Apr. 23, 1912.

Application filed May 12, 1911. Serial No. 626,713.

To all whom it may concern:

Be it known that I, WILLIAM ELLIS, a citizen of the United States, residing at Harrod, in the county of Allen and State of Ohio, have invented new and useful Improvements in Spark-Plugs, of which the following is a specification.

This invention relates to spark plugs for internal combustion engines, and it has for 10 its object to provide a simple and improved construction whereby the plug is provided with two separate and independent sparking devices, properly insulated from each other and so arranged that in the event of 15 one of said devices being disabled, the simple adjustment of a switch will enable the other unit of the sparking device to be thrown into active operation so that the operation of the engine with which the device 20 is associated may be continued without interruption, the instalment of a new sparking device being postponed until a more convenient season.

With these and other ends in view which 25 will readily appear as the nature of the invention is better understood, the same consists in the improved construction and novel arrangement and combination of parts which will be hereinafter fully described 30 and particularly pointed out in the claims.

In the accompanying drawing has been illustrated a simple and preferred form of the invention, it being, however, understood that no limitation is necessarily made 35 to the precise structural details therein exhibited, but that changes, alterations and modifications within the scope of the claims may be resorted to when desired.

In the drawing,—Figure 1 is a view in 40 elevation of the improved spark plug. Fig. 2 is a vertical sectional view of the same. Fig. 3 is a side elevation of the switch used in connection therewith.

Corresponding parts in the several figures 45 are denoted by like characters of reference.

The casing 1 of the improved spark plug is externally threaded at 2 for engagement with the engine head 3, and said casing is provided with a wrench seat 4 to enable it 50 to be conveniently adjusted and tightened. The upper or outer end of the casing constitutes a packing box for the reception of packing 5 which is retained by means of a gland 6 of ordinary construction. The lower 55 end of the shell or casing 1 is provided with

inwardly extending prongs 7, 7' constituting electrodes.

The shell contains an insulating plug 8 of porcelain or other suitable material, said plug being provided with a downwardly 60 extending web 9 and with electrodes 10, 10' extending longitudinally therethrough, said electrodes terminating adjacent to the prongs 7, 7'. The upper extremities of the electrodes are provided with U-shaped 65 brackets 11, 11' adapted to be engaged by a switch lever 12 which is connected by an insulating block 13 of porcelain or other suitable material with a resilient supporting member 14, the latter being bolted or 70 otherwise secured upon the head of the engine. The switch lever 12 has a handle 15 whereby it may be conveniently manipulated and is provided with a binding post 16 for connection with the timer wire 17 whereby 75 connection is made with the magneto, battery or other electrical connection in any customary and well known manner.

It will be observed that the spark gap between the prong 7 and the electrode 10 80 is entirely separated from the spark gap between the electrode 7' and the prong 10' by the web 9, so that the sparking of the one set of electrodes will not injuriously affect the other set. 85

In the operation of this device, if the electrodes at one side of the device should be burned out or refuse to act, the simple switching of the lever 12 to the opposite bracket 11 or 11', as the case may be, will 90 cut the first electrode from and include the second electrode in the circuit, thus restoring the device to operativeness.

Having thus described the invention, what is claimed as new, is:— 95

1. In a spark plug, a shell having a plurality of inturned prongs at its lower end, and an insulating plug in the shell having a downwardly extending web forming a partition between the prongs, electrodes extending through the plug, said electrodes terminating at opposite sides of the web, each electrode adapted to spark to one of the inturned prongs, and each electrode having switch engaging means at its upper end, and a resiliently supported switch lever to alternately engage the switch engaging means of the several electrodes. 100

2. In a spark plug, a shell having prongs at its lower end, an insulating plug having 110

a downwardly extending web forming a partition between the prongs, electrodes extending through the plug at opposite sides of the web and terminating adjacent to the 5 prongs, each of said electrodes being provided with switch engaging means at its upper end, a resilient supporting member, a switch lever, an insulating block connecting the switch lever with the supporting member, said lever being adapted for alter-

nate engagement with the electrodes, and a binding post and a handle upon the switch lever.

In testimony whereof I affix my signature in presence of two witnesses.

WILLIAM ELLIS.
